UNITED STATES PATENT OFFICE.

JAMES B. SELLS, OF BLUFF CITY, TENNESSEE.

WHEEL-FRAME FOR PLOWS OR CULTIVATORS.

SPECIFICATION forming part of Letters Patent No. 644,875, dated March 6, 1900.

Application filed October 12, 1899. Serial No. 733,363. (No model.)

To all whom it may concern:

Be it known that I, JAMES B. SELLS, a citizen of the United States, residing at Bluff City, in the county of Sullivan and State of 5 Tennessee, have invented new and useful Improvements in Wheel-Frames for Plows or Cultivators, of which the following is a specification.

This invention relates to certain new and 10 useful improvements in wheel or sulky plows, the object being to provide a wheel-supported frame, the parts thereof being so constructed as to provide means for attaching to the frame and operating therefrom either a breaking plow—to wit, one with a point, mold-board, and landside—or cultivators, as shovel-plows, harrows, or other implements which are attached to beams.

The invention consists in the general construction and combination of the parts, as 20 will be hereinafter set forth and specifically pointed out in the claims.

In the accompanying drawings, which form a part of this specification, Figure 1 is a side 25 elevation showing a plow applied to a wheel or sulky frame constructed in accord with my invention. Fig. 2 is a rear elevation of the structure shown in Fig. 1. Fig. 3 is a plan view of Fig. 1. Fig. 4 is a side elevation 30 showing the arrangement or organization of parts of the frame for use as a cultivator or shovel-plow. Fig. 5 is a plan view of the parts when arranged as shown in Fig. 4. Fig. 6 is a detail perspective view of the locking de- 35 vice for one of the levers, and Fig. 7 is a perspective view of a part of the means employed to support the cultivator-beams.

The frame is preferably made up of iron or steel and comprises a flat bar A, the ends 40 of which are bent at right angles to form the outer side portions of hangers. To the under side of the bar A is rigidly secured a bar A', which is of less length than the bar A, and the ends depend and form the inner side of 45 the hangers, which construction braces the cross-bar of the frame and prevents its sagging under the weight which is placed thereon. The lower ends of the hangers A², which are formed by the downwardly-bent end portions 50 of the flat bars A and A', have journaled therein crank-axes a, and above the bearings are

bolts which connect to the hangers segmental plates a' and the ends of bars which constitute a part of the frame. The upper ends of the segmental plates are connected to the frame immediately above the hangers, and said plates have openings to receive the bolts of levers which operate both the crank-axes or cultivator-frames, as will be hereinafter set forth.

The forward portion of the frame is made up of a flat bar the ends of which are bent downward and rearward, the lower ends being bolted to the hangers by bolts which pass through the coiled ends of the segmental 65 plates, said plates having laterally-projecting side pieces which hold the side pieces of the hanger apart, so as to prevent their being drawn together when the bolt is tightened. To the inclined portion of the bars A³ are 70 pivoted the forward ends of levers B, said levers having spring-actuated bolts or catches attached thereto in the usual manner for engagement with the openings in the segmental plates, the bolts being connected by wires or 75 rods to hand-grips which are pivoted adjacent to the grasping portion of the levers. The bars A, A', and A³ of the frame are connected by bars, as shown more especially in Figs. 3 and 5, and the general construction 80 and arrangement is such as to provide a frame which is extremely rigid and light and one that can be manufactured without the use of special tools.

The horizontal bars of the frame have suitable openings through which pass bolts or equivalent means for connecting to the upper faces of said bars a tongue B', also the support for the driver's seat B². The depending sides of the hangers A² have several perforations, which are in line with each other, so that the position of a bail which is pivotally attached to said hangers may be changed, and the inclined portions of the bars A³ have openings below the fulcrum of the lever to 95 receive the upper ends of links a⁴, the lower ends of the links being attached to crank-axes a, which are journaled in the hangers, the outer ends of said crank-axes having mounted thereon the supporting-wheels. The 100 upper end of the link a⁴ is constructed so that it may engage with a lever B or with one of

the perforations a^3 in the bar A^3 , especially when it is desired to hold the axles in a fixed position.

When the frame is used with a breaking-plow, the supporting-wheels may be positioned, as shown in Fig. 1, so that one of the axles will incline forward and the other rearward to position the supporting-wheel nearest the plow in advance of its point. To raise the frame, power is exerted upon the levers B by bearing down upon the rear ends thereof, which is an advantage, as the weight of the driver or plowman is used to accomplish this end.

To the tongue B' , between the horizontal cross-bars $A A' A^3$ of the main frame, there are attached depending bars b' , which are braced by inclined bars b^2 , the upper ends of which are adjustably connected to the tongue, and near their lower ends is a bolt b^3 , which extends across the plow-beam and connects the bars together and limits the upward movement of the plow-beam, its downward movement being restrained by a bolt b^4 , which passes through the bars b' underneath the plow-beam and rear of its clevis. The loop which is formed by the bolt b^3 , the ends of the bars b' , and the bolt b^4 is of such size that the plow-beam may move freely therein to a limited extent, and the object of the series of perforations in the upper ends of the bars is to provide for a range of adjustment, so that plows of different sizes can be attached to the frame.

A lever C is fulcrumed to the tongue B in advance of the frame, and it extends rearward toward the driver's seat, and adjustably connected to this lever is a link c , through the lower end of which is passed one of the short ends of a bail D . This bail is pivoted to the inner side pieces of the hanger and is connected to the plow-beam by means of a suitable clip. The tongue carries in advance of the frame a catch or plate c' , with which a detent or ratchet-tooth on the link c is adapted to engage when the lever is raised, and the lower end of said link is moved to one side, so as to be normally held in engagement with the plate by a spring c^2 , one end of which bears upon the link, while the other end contacts with the bent portion of the bail. To disconnect the tooth or detent from the plate, with which it engages to prevent the bail swinging on its pivot, the end of the lever is moved sidewise and is depressed. Such movement forces the link downward and raises the rear portion of the bail, which is attached to the plow-beam. It will be thus seen that the downward movement of the lever is prevented by the catch, and upward movement is limited by the inturned end of the bail contacting with the tongue. Where the bail is fulcrumed or pivoted to the hangers, said bail is flattened and provided with openings, through which pass the connecting-bolts.

When the parts are organized as shown in Fig. 1 of the drawings and the lever is locked,

the plow will be prevented from rising out of the ground.

A sulky-plow constructed as shown provides a cheap, simple, and practical implement which may be used with plows of different characters and sizes. The supporting-wheels may be adjusted so that the plow will enter the ground to the depth desired, and the axles can be turned in their bearings to suit the inclinations of the land, as on a hillside, the plow may be raised clear of obstructions by depressing the lever which is pivoted to the tongue, and the arrangement of the seat is such that the driver can readily reach the plow with his foot to clean the same or remove obstructions therefrom when the plow is in use, and as the driver's weight is rear of the axles it will tend to balance the frame. When it is desired to hold the plow clear of the ground, the lever C can be depressed and its end caused to engage a hook c^4 , attached to the rear portion of the tongue.

When it is desired to use the frame hereinbefore described as a frame for cultivators, shovel-plows, or implements of a like nature, the position of the bail is changed, the cross-bar thereof being attached to the upper ends of the hangers, and the now forward and depressed ends of the bail are connected to the front ends of cultivator-beams, and braces $g g$ engage with the inturned ends of the bail and extend upward to the bolt which attaches the tongue to the front cross-bar A^3 . The crank-axles are made fast to the main frame, so that they will preferably incline forward. To the hangers, at points where the bail was previously attached, are pivoted cranks $E E$, which have arms $e e'$, which engage, respectively, with slots or loops e^2 in the levers B , the other arms engaging rollers $f f$, which have circumferential grooves and are held in close proximity with each other by staples which are connected to the upper ends of bars F , which bars have near their central portions quarter-bends, the lower ends being adjustably connected to the beams of the cultivators. By the construction shown the frame, when the plow is detached, may be used as a straddle-row cultivator or for other purposes. The crank-arms and rollers provide means for moving the cultivators side-wise while in use, so that they may be brought near to plants which are not directly in a row, or they may be moved to one side to clear obstructions. By depressing the rear ends of the levers B the cranks will be rocked and the rear ends of the cultivators raised. The cultivators may be of any suitable type, according to the purpose for which they are used, and in some instances the cultivator-beams are provided with caster-wheels, which may coact with the wheels to support the main frame.

I claim—

1. In a sulky-frame for plows and cultivators, the combination with two flat bars which are connected to provide a horizontal cross-

bar of double thickness, said bars having downwardly-extending ends to provide hangers, of a bar having downward and rearward extended ends which ends are connected to the outer depending sides of the hangers, bars connecting the horizontal bars to each other, a seat-support which extends rear of the frame, levers pivoted to the inclined side bars of the frame, and links which connect the levers to crank-axes, said crank-axes being journaled in the lower portion of the hangers, substantially as shown and for the purpose set forth.

2. In combination with a wheel-supported frame, a tongue rigidly attached to the frame on one side of its center, a lever pivoted to the tongue in advance of the frame, a link adjustably attached to the lever near its fulcrum, said link having a projecting portion or catch as shown, a plate carried by the tongue with which the catch on the link engages, a bail which is connected to the frame and to the lower end of the link and a spring which engages with the bail and link, for the purpose set forth.

3. In a sulky-frame for plows and cultivators constructed substantially as shown and provided with hangers, the combination with a bail having inturned ends at its forward portion and apertures through the side pieces thereof, of hangers having perforations whereby the bail may be attached to said hangers at different points, for the purpose set forth.

4. In a sulky-frame for plows and cultivators, the combination with a frame constructed substantially as shown and provided with depending hangers and inclined side bars which are connected thereto the hangers having apertures at different points, levers pivoted to

the inclined bars and adapted to engage with segmental plates carried by the hangers, links detachably connected to the levers, said links being adapted to be placed in engagement with the apertures in the inclined bars of the frame, crank-axes journaled to the hangers and provided with links as shown, a bail pivoted to the hangers and connected to the beam of an implement and to a lever which is pivotally attached to a tongue in advance of the wheeled frame, substantially as shown.

5. In a sulky-frame for plows and cultivators, the combination with a pair of connected bars A A', the ends of which are bent at right angles to provide hangers A², crank-axes journaled in the lower ends of the hangers, a bar A³ which extends parallel with the bars A, A' hereinbefore mentioned, the end portions of said bar A³ extending downward and rearward and being connected to the hangers above the axle, a tongue carried by the frame, a bail D pivotally attached to the hangers, said bail being adapted to engage with an implement carried by the frame, levers B B pivoted to the inclined bars of the frame so as to extend rearward said levers having spring-actuated bolts which engage with segmental plates a' attached to the hangers, said levers determining by their position the depth with which the cultivators or plow will enter the soil, the parts being organized substantially as shown.

In testimony whereof I have hereunto set my hand in presence of two subscribing witnesses.

JAMES B. SELLS.
